DESIGN FOR A BOOKMARK

William W. Heil, Dumont, N. J.

Application December 5, 1945, Serial No. 124,393

Term of patent 14 years

(Cl. D6—2)

To all whom it may concern:

Be it known that I, William W. Heil, a citizen of the United States, residing at Dumont, in the county of Bergen and State of New Jersey, have invented a new, original, and ornamental Design for a Bookmark, of which the following is a specification, reference being had to the accompanying drawing, forming part thereof.

I claim:

The ornamental design for a bookmark, as shown.

WILLIAM W. HEIL.
